C. F. JOHNSON

CARBURETOR

Filed Jan. 31, 1916

Patented Oct. 7, 1924.

1,510,520

UNITED STATES PATENT OFFICE.

CHESTER F. JOHNSON, OF DETROIT, MICHIGAN.

CARBURETOR.

Application filed January 31, 1916. Serial No. 75,396.

To all whom it may concern:

Be it known that I, CHESTER F. JOHNSON, a citizen of the United States, and resident of Detroit, Wayne County, State of Michigan, have invented certain new and useful Improvements in Carburetors, of which the following is a specification.

This invention relates particularly to carburetors or fuel mixing devices for internal combustion engines.

One of the objects of this invention is to provide improved means, for producing an efficient fuel mixture for internal combustion engines, wherein the quality may be accurately controlled for variable operating conditions by automatic or manually operable devices.

Another salient object of this invention is to provide an improved carbureting device, which, while efficient in operation, easily lends itself to manufacture, and permits of a facile and accurate control under variable conditions.

Broadly speaking, this invention may be said to consist in the provision of a carburetor, comprising a mixing chamber having primary and secondary air ports, independent valve devices therefor, the secondary air valve being adapted to be actuated by the air flowing through the primary port.

This invention also consists of various other features of construction, all of which will clearly appear from the following description, taken in connection with the accompanying drawings, which form a part of this specification, and in which:

Figure 1 is a vertical section through a carburetor, embodying a preferred form of this invention;

Figure 2 is a transverse section, substantially on the line 2—2 of Figure 1;

Figure 3 is a fragmentary perspective view of the primary air valve operating lever; and

Figure 4 is a plan view of a sleeve valve member.

Referring to the drawings, 10 represents a carburetor body having a downwardly extending integral tube 11 formed therein and providing a guide for a slideable sleeve valve 12, which is adapted to be mounted in its interior. The carburetor body is also provided with a pair of communicating opposed lateral ports 13, which, in the illustrated embodiment, form an intake for all of the air

entering the carburetor. A member or diaphragm 15 forms a lower wall for the carburetor and the upper wall, or cover of the usual float chamber. The diaphragm has a central depressed portion or cup 16 formed therein, and also has upwardly extending flanged portions 17, which are provided with lateral primary air ports 18, which are in constant communication with the intake 13. A fuel nozzle 19, having a mouth or discharge port 20, and inlet port 21, is shown as formed integral with the member 15. This member is also provided with an integral nipple 22 having an externally threaded portion 23, to which the usual fuel feed pipe, not shown, may be connected. A passage 24 may be formed in the interior of this nipple and is provided with a port 25, which is adapted to be controlled by any suitable valve mechanism, comprising a valve member 26, and the usual float 27, which may be pivoted, as at 28, on the member 15. A float chamber bowl or shell 29 may be secured in position by means of a wing nut 30, which may have a threaded connection, as at 31, to the lower end of the fuel nozzle 19.

A mixing or strangle tube 32, which may have a central portion tapering towards its lower end, and a laterally extending portion 33, on which may be formed a downwardly extending flange 34, may be properly seated on a shoulder 35 formed on the central portion of the member 15. Formed in the flange 34 may be lateral ports 36, which are adapted to be brought into and out of registration, with the ports 18 in the member 15, by a movement, such as rotation of the mixing tube 32, by means of a control lever 37, comprising a handle and ring portion 38, which is adapted to be brazed, or otherwise secured to the mixing tube 32.

It will be noted that the mixing chamber is provided with a laterally extending slot 39, through which the handle of the lever 37 extends. It will also be noted that an arcuate member 39' may be formed integral with the handle portion of the lever 37, or suitably secured to it, this member being adapted to slide over the interior surface of the mixing chamber, and at all times to cover the slot 39 so that no air may be drawn therethrough into the interior of the mixing chamber.

The usual throttle valve 40 may be arranged on a shaft 41, which may be mounted

adjacent the outlet of the carburetor body 10 and is adapted to be controlled by the usual arm 42. It will be noted that the sleeve valve 12 is provided interiorly thereof with a cage or spider 43, which may be formed integral therewith, or suitably secured thereto. This cage has transverse web portions 44 and a downwardly extending leg 45, on which may be arranged a plate 46 for lifting the sleeve valve, as will more fully appear hereinafter. Normally the bottom portion 47 of the sleeve 12 is adapted to rest on the ring portion 38 of the mixing tube 32, and it is limited in its upward 15 movement by an integrally formed inwardly extending flange 48.

Having thus described the general construction and arrangement of the parts, the operation of my carburetor will be understood as follows: Assuming the throttle to be in substantially the position illustrated in Figure 1, and the motor to be running under light load, the sleeve valve 12 will be in its lowermost position; namely, so that its bottom portion 47 will rest against the ring portion 38 of the mixing tube 32, and if the handle 37 is in the position shown in Figures 1 and 2, primary air will be drawn in the carburetor at 13, flowing downwardly 20 through the carburetor, thence through the registering ports 18 and 36, around the outside of the mixing tube 32 and upwardly through the mouth 49 formed between the discharge port 20 of the fuel nozzle and the 25 mixing tube 32.

Of course it will be understood that as the air passes by the mouth of the nozzle, fuel will be drawn therefrom, and after the air is mixed with the fuel, it will be then drawn upwardly through the mixing tube and through the interior of the sleeve 12 to the motor. It is assumed that with the motor operating under the conditions just described, insufficient suction or vacuum is 30 created to permit the lifting of the plate 46 by the incoming primary air. However, if the suction of the motor is increased and the velocity of the incoming primary air is quickened, the force directed against the bottom of the plate 46 will be found sufficient to lift the plate and the auxiliary valve 12, thus gradually enlarging a port 50 between the bottom 47 of the sleeve valve 12, tube 11 and the laterally extending portion 35 of the strangle tube 32. The auxiliary air will flow upwardly in the same manner as the mixture which is formed by the primary air and the fuel issuing from the fuel nozzle, and will tend to lean this mixture. The amount of the opening of the port 50 and the distance which the sleeve valve 12 and the plate 46 will be raised will, of course, depend on the flow of primary air, and when the quantity or velocity of this 60 air decreases, the valve 12 will immediately

fall. So long as the velocity of the incoming primary air is constant, the height of the sleeve valve 12 is substantially stationary, because of the balance obtained between the weight of the valve and the upward flow of the primary air.

It will also be understood that the raising and lowering action of the plate 46 performs the function of a valve in co-operation with the strangle tube 32, because of the tapered formation of the latter; that is, as the plate 46 rises, it necessarily enlarges the unrestricted area of the interior of this tube.

While I have described and illustrated an auxiliary air valve of sleeve construction, which is adapted to be slidably arranged in the mixing chamber, it is not essential that a secondary air valve be used, and while the strangle tube is adapted to be rotated, it will, of course, be understood that these and other details of construction shown are merely illustrative and that various modifications and changes may be made by one skilled in the art, without departing from the spirit and scope hereof, as defined by the appended claims.

Having thus described my invention, what I claim and desire by Letters Patent is:

1. In a carburetor, the combination of a carbureting portion, provided with a bottom having a central depression, means for conducting fuel into said chamber adjacent said depression, a downwardly tapering tube rotatably mounted in said chamber, and extending into said depression, a cylindrical valve slidably mounted within the chamber and adapted to be raised by the flow of air through said tapering tube, said tube being provided with means for varying the flow of air therethrough by a rotation thereof.

2. In a carburetor, the combination of a body, a float chamber secured thereto, the bottom of the body forming a cover for said float chamber and having a central depressed portion, a fuel nozzle adjacent said depressed portion, a tapering rotatable tube mounted in said body, and extending downwardly into said depressed portion, said body having a primary air port, said rotatable tube being provided with means for varying the flow of air through said port, said body also being provided with a secondary air port, and a slideable sleeve valve mechanism for controlling said latter port.

3. In a carburetor, the combination of a body, a float chamber secured thereto, the bottom of the body forming a cover for said float chamber and having a central depressed portion, a fuel nozzle adjacent said depressed portion, a tapering rotatable tube mounted in said body, and extending downwardly into said depressed portion, said

- body having a primary air port, said rotatable tube being provided with means for varying the flow of air through said port, said body also being provided with a secondary air port, and a slidable sleeve valve mechanism for controlling said latter port, said sleeve valve mechanism being provided with means whereby it is actuated by the flow of air through said primary port.
- 19 4. In a carburetor, the combination of a carburetor chamber having a bottom portion which is provided with a diaphragm having a downwardly extending central portion, a fuel nozzle arranged adjacent said central portion, a cylindrical tube arranged in said carbureting chamber having a lateral air port formed therein, a sleeve valve slidably mounted in said tube and adapted to normally close said air port, and a rotatable downwardly tapering tube arranged within said central portion, said carbureting chamber being provided with another air port, said rotatable tube being provided with
- 25 means for controlling the flow of air therethrough.
5. In a carburetor, the combination of a carburetor chamber having a bottom portion which is provided with a diaphragm having a downwardly extending central portion, a fuel nozzle arranged adjacent 30 said central portion, a cylindrical tube arranged in said carbureting chamber having a lateral air port formed therein, a sleeve valve slidably mounted in said tube and adapted to normally close said air port, and a rotatable downwardly tapering tube arranged within said central portion, said carbureting chamber being provided with another air port, said rotatable tube being provided with means for controlling the 35 flow of air therethrough, said sleeve valve being adapted to be actuated by the flow of air through said latter mentioned port.

In testimony whereof, I affix my signature.

CHESTER F. JOHNSON.
